UNITED STATES PATENT OFFICE.

CHARLES E. RUTTAN, OF LOS ANGELES, CALIFORNIA.

HALF DOOR FOR AUTOMOBILE INCLOSURES.

Application filed May 26, 1924. Serial No. 715,796.

This invention has to do generally with doors for automobile inclosures, and is more particularly concerned with doors and their mountings as used in connection with inclosures for converting automobiles of the so-called "open type" into closed or semi-closed cars.

Certain peculiar problems present themselves in connection with the installation of these doors. For example, the available storage space for the doors is small, and yet the comparatively large rigid doors must be moved out of sight and be protected against breakage when it is desired to use an equipped automobile in "open" condition. The major portion of the door is in the nature of a glass panel, thus precluding the use of joints whereby the door might otherwise be folded into compact form and then moved into a comparatively small storage space.

Furthermore, to be of full efficiency, the doors must be quickly and easily movable from a position of storage into operative position, and vice versa, without the use of tools and without exposing the door to treatment which might result in breaking the glass panels.

It is very desirable from the standpoint of economical manufacture that an inclosure door of standard design fit cars of different makes, and this immediately brings up the matter of hinge alinement.

Different makes of cars have different types of body door hinges, some of them having "flush" hinges, others having offset hinges, some hinges are in vertical alinement, others are angularly disposed with respect to the vertical, etc. Since the inclosure door (equipped with standard hinges, for instance) must move pivotally on its hinges coincidently with the movement of the body door on its hinges, it will be apparent that it is a matter of considerable difficulty to provide a hinge mounting for the inclosure door which will be competent to function properly irrespective of the type of body door hinge installed on a given car.

Therefore, it is among the objects of my invention to provide an inclosure door and a mounting therefor which effectually meets the problems noted above, as well as other problems not mentioned. In addition, it has been one of my purposes to provide a mounting which is slight and neat, and which does not call for the use of attach-

ments of unpleasing appearance. I have provided a structure whereby, when the inclosure door is out of operative position, there is little or no visual evidence from the exterior that the car is of a convertible nature; while, when the door is in operative position, the car has the appearance of a permanently closed or semi-closed vehicle.

Generally described, the invention consists of a door frame which includes a post for hingedly supporting the door, the frame being secured on the vehicle body in such a manner that it is movable from a concealed position clear of the body doorway into such a position that it brings its door into vertical alinement with the body door, and its hinges are brought approximately into axial alinement with the body door hinges. The two doors are then tied together so they swing as one.

In the preferred embodiment of the invention, novel means are provided whereby the hinges of the body door and inclosure door may be considerably out of axial alinement without interfering with the proper swinging of the composite door; for, during door movement, the door frame is free to move relative to the car body, so, in effect, the out of alinement arrangement of the door hinges causes relative movement between the two half-door frames, whereas, were the two frames to be rigidly connected, the disalinement of the hinges would, in the absence of means for allowing relative movement between hinges, set up a binding action which would prevent proper door swing.

By reason of the last-mentioned feature, I am able to employ "flush" hinges for the inclosure door, even though the car on which the installation is made has hinges which are considerably offset from the face of the body door.

I will point out further features of novelty and objects of the invention in the following detailed description, reference being had to the accompanying drawings, in which:

Figure 1 is a side elevation of an automobile equipped with my structure;

Fig. 2 is an enlarged horizontal section on line 2-2 of Fig. 1;

Fig. 3 is an enlarged horizontal section on line 3-3 of Fig. 1;

Fig. 4 is an enlarged vertical section on line 4-4 of Fig. 1;

Fig. 5 is an enlarged fragmentary eleva-

tion of the door frame and its mounting as viewed from the interior of the car; and

Figures 6, 7 and 8 are diagrammatic views illustrating certain principles of operation which will be fully set forth in the body of the specification.

In Figure 1 I have shown my invention applied to an automobile equipped with a so-called "California top" 10, wherein the rear compartment 11 of the car is partially enclosed by glass side panels 12 which are supported within semi-rigid side curtain 13. When in storage (or out of operative position) the inclosure door structure, generally indicated at 14, is adapted to be concealed behind the side curtains and panels. However, this showing of the invention in connection with a particular type of top is not to be construed as in any way limiting the invention to this specific application, for it may be applied to cars having flexible or removable side curtains, or a fixed, partially enclosing panel may be installed on cars which come from the factory with their sides entirely open between the side of the body and their collapsible tops.

Furthermore, while I have illustrated and will describe a structure which closes off only the rear compartment of the vehicle (in other words, makes a semi-closed car out of an open car) the door structure may be duplicated for the front compartment of the car and thereby serve to convert an open car into a full-closed car.

I will first assign numerals to certain standard parts of the vehicle, so future reference to these parts in their association with my device may be more readily followed. Body 15 has a door 16 swung on hinges A, and, for the time being, we will assume these hinges are in vertical alinement and substantially flush with the outer face of the body and door. The upper edge 18 of body 15 is in horizontal alinement with the upper edge 19 of door 16 when the latter is closed, and overlying and substantially paralleling edges 18 and 19 is the top rail or bow 20 which extends lengthwise of the car and may serve as the marginal brace for top 10.

Secured to rail 20, or to any other suitable supporting member carried by top 10, is the track 21, upon which hangers 22 are adapted to slide longitudinally of the car. Suspended from hangers 22 is the L-shaped attachment member 23 which preferably includes an upright 24 and a horizontal rail 25.

Hinged on upright 24 at B is the door supporting frame 26 which includes posts 27 and 28 and top or cross-bar 29. Hinged at C to post 28 is the door 30 which includes a transparent panel 31. It is evident that attachment member 23, frame 26 and door 30 may be swung into a common vertical plane (which relative positions they are adapted to assume when in storage); or that the frame

and door may be swung on their respective hinges to bring them into different vertical planes.

When the elements thereof are nested so as to lie in a common vertical plane, the assembly just described may be moved along track 21 longitudinally of the car and behind curtain 13, where they will be out of sight from the exterior of the car and will entirely clear the doorway in the car body. An angle iron 75 guide 32, paralleling track 21, may be secured on the upper edge 18 of the car body, and serve to retain the lower edge of the inclosure door and its associated structure in a position adjacent curtain 13.

Since, when in storage, the inclosure door structure lies behind curtain 13 and hence back of the outer face of the body, and since it is desirable that the outer face of door 30 be approximately flush, guide 32 and track 21 80 are disposed angularly with respect to the outer face of body 15, the forward end of track 21 being so disposed that it brings the forward post 23 substantially flush with the outer face of the body when the nested door structure is moved to the position of Fig. 1. The structure is thereafter moved within itself, in a manner to be described, to bring door 30 flush with door 16.

First, let us assume an ideal condition 95 where hinges A are in vertical alinement, and with the structure moved as above described, hinges C are in axial alinement with hinges A, or that a slight movement of frame 26 on hinges B suffices both to bring hinges A 100 and C into axial alinement and to bring the hinged side of door 30 flush with door 16. Then by swinging door 30 outwardly on hinges C, the two complementary half-doors 30 and 16 may be brought into flush register 105 and by tieing them together by latches 33, or any other suitable tie or clamp devices, the two doors cooperate to form a composite door for the rear compartment. Since hinges A 110 and C are in axial alinement, the two doors swing as one and without any relative movement between them or their hinges.

In order to differentiate between doors 16 and 30 in the appended claims, I will there refer to door 16 as a "body door" and to door 115 30 as a "half door."

In certain situations the ideal conditions above noted may be brought about without the use of the hinged connection between door frame 26 and attachment member 23, and in such situations the separate attachment member 23 may be eliminated, and said door frame may be attached directly to hangers 22. I wish it to be understood that this variation lies within the scope of my broader claims, as does also a variation wherein the door frame is moved to and from operative position by swinging it through a horizontal plane about hinges B; that is, instead of sliding the frame to and from a position behind curtain 13, at- 120 125 130

tachment member 23 might be capable of little or no sliding movement, but by properly mounting hinges B the door frame might be swung through compartment 11 from the 5 position to Fig. 1 to a position behind curtain 13.

Fig. 2 illustrates the position of the structure when it has been first moved out of storage, it being assumed that hinges C exactly 10 superpose hinges A. Figure 3 shows door 30 as having been swung outwardly on hinges C until the forward edge of said door is approximately flush with door 16, in which position it is clamped by latches 33.

15 Even though hinges A and C are not in axial alinement when the doors are rigidly clamped together, the device still functions effectively and without interference or door bind. To discuss this phase, let us assume 20 a case where hinges A project considerably from the side of body 15, hence making it impossible to line up flush hinges C without swinging frame 26 on hinges B to such an extent that door 30 would project considerably 25 beyond door 16, an undesirable condition.

In Fig. 6, hinge A is shown as considerably offset with respect to hinge C, and yet doors 16 and 30 are tied against relative movement.

As door 16 swings outwardly about A, 30 hinges C move both rearwardly and outwardly. The rearward movement is accommodated by the longitudinal movement of the entire frame 26 and attachment member 23, hinges B moving back to dotted line position. The outward movement is accommodated by the frame 26 swinging outwardly 35 about hinges B. Of course, during door closing movements, frame 26 moves longitudinally and forwardly along track 21 and the frame swings inwardly about hinges B. 40

Thus, relative movement occurs between the frames (body 15 and frame 26) of the two doors rather than between their points of pivotal mounting, and therefore the two 45 doors are free to swing as one without hinge interference and without either door binding. Another condition met with, is the positioning of hinges A so they are out of vertical alinement. This condition arises due to 50 the bow shape of some doors, that is, the door bows inwardly at its lower edge. Consider Fig. 7, where an exaggerated example of this condition is shown to exist. The common axis D of hinges A inclines with respect 55 to the vertical and hence door 16 will swing to the dotted line position when open. However, door 30 preferably extends vertically when closed and in order that door 30 may follow door 16 during pivotal movement 60 thereof, hinges C may be offset as shown in this figure, so they are coaxial with hinges A. However, with the use of my hinged door frame it is not necessary to resort to offset hinges C for accomplishing the desired end, 65 for hinges C may be flush, as previously de-

scribed, and as diagrammatically indicated in Fig. 8, without destroying the effectiveness of the device even under the body hinge condition illustrated. For frame 26 swings about hinges B to allow the outward movement of 70 hinges C and said frame is made of material having sufficient resiliency to yield somewhat and allow the frame to bend and twist sufficiently to accommodate the differential movement of the upper and lower parts of door 30 and the variable inclination of said door as 75 it swings about hinges C.

It will be noted that track 21 extends clear to the front of the car so door structure 14, or a duplicate thereof, may be moved forwardly 80 to enclose forward compartment F and to bring door 30 into register with body door G. As soon as structure 14 is moved forwardly a sufficient distance to clear curtain 13 and guide 32, its lower edge is unconfined and free 85 and therefore the structure may be rocked about track 21, transversely of body 15, until the two doors are locked in alinement. This feature is of value for various reasons, for instance, in some instances the back H of the 90 front seat projects beneath track 21, and therefore, in moving past this back, the door structure may be swung outwardly to avoid interference.

It will be understood that while I have illustrated a preferred embodiment of my device, the drawings and description are to be considered merely as illustrative of and not restrictive on the broader claims appended hereto, and therefore I do not wish to be limited to the structure shown and described except for such limitations as a fair interpretation of the appended claims may import.

Having described a preferred form of my invention, I claim:

1. In an inclosure for the compartment of an automobile body having a hinged door opening to the compartment, a door structure 110 slideable longitudinally along the upper edge of the body door into and out of operative position and including a half-door which is complementary to and is movable hingedly with the body door when the door structure is in operative position, and attachment means connecting the body and door structure and adapted to allow relative movement therebetween whereby the door structure is slideable 115 into and out of operative position without being detached from the body.

2. In an inclosure for the compartment of an automobile body having a hinged door opening to the compartment, a door structure 120 slideable longitudinally along the upper edge of the body door into and out of operative position and including a half-door which is complementary to and is movable hingedly with the body door when the door structure is in operative position, attachment means connecting the body and door structure and adapted to allow relative movement therebe- 125

tween whereby the door structure is slidable into and out of operative position without being detached from the body, and means for detachably coupling the two doors when 5 they are in complement.

3. In a movable inclosure for the compartment of an automobile having a hinged door, a door structure that includes a frame which is slidable longitudinally along said hinged 10 door into and out of operative position with respect thereto, a door hinged to the frame and complementary to the body door, means for supporting the frame from the body, and means for securing the two doors together.

15 4. In a movable inclosure for the compartment of an automobile having a hinged door, a door structure that includes a frame, a door hinged to the frame and complementary to the body door, means for securing the doors 20 together and against relative movement, and means for connecting the frame and body whereby they are capable of relative movement to allow said doors to swing upon their 25 hinges irrespective of the relative position of said hinges.

5. In an inclosure for the compartment of an automobile that has a top spaced above the body of the vehicle and that has a hinged door in the body, a track supported by said 30 top and extending longitudinally of the automobile, a door structure that includes a hinged half-door complementary to the body door, said structure being suspended from the track and movable therealong in a manner to carry 35 said half-door into and out of vertical alinement with said body door, said body door and said half door each being hingedly movable when in vertical alinement.

6. In an inclosure for the compartment of 40 an automobile having a hinged door in its body, a door structure that includes a frame, and a half-door hinged to the frame and complementary to the body door, said frame being slidable longitudinally along the upper 45 edge of the body door into and out of operative position, whereby said half-door is movable into and out of vertical alinement with the body door without detaching said frame from said body.

50 7. In an inclosure for the compartment of an automobile having a hinged door in its body, a door structure that includes a frame, a half-door hinged to the frame and complementary to the body door, said frame being slidable longitudinally along the upper 55 edge of the body door into and out of operative position whereby said half-door is movable into and out of vertical alinement with the body door without detaching said frame from said body, and means for detachably coupling the two doors when they are in alinement.

60 8. In an inclosure for the compartment of an automobile having a hinged door, a door structure that includes a frame, a door hinged 65

to the frame and complementary to the body door, said frame being movably mounted on the body whereby said half-door is movable into and out of vertical alinement with the body door without detaching said frame from 70 said body, and means for detachably coupling the two doors and holding them against relative movement when they are in alinement; said body and frame being capable of relative movement after the doors are coupled. 75

9. In an inclosure for the compartment of an automobile having a hinged door, a door structure that includes a frame, and a door hinged to the frame and complementary to the body door, said frame being movable longitudinally and pivotally on the body whereby said half-door is movable into and out of vertical alinement with the body door without detaching said frame from said body. 80

10. In an inclosure for the compartment of an automobile having a hinged door, a door structure that includes a frame, a door hinged to the frame and complementary to the body door, said frame being movable longitudinally and pivotally on the body whereby said half-door is movable into and out of vertical alinement with the body door without detaching said frame from said body, and means for detachably coupling the two doors when 90 in alinement, said body and frame being capable of relative longitudinal and pivotal movement when the doors are coupled. 95

11. In an inclosure for the compartment of an automobile having a hinged door, a door structure that includes an attachment member longitudinally movable over the side of the compartment, a frame hinged to the attachment member and movable through a horizontal plane about its hinges, and a half-door hinged to said frame and complementary to the body door; the attachment member being movable to carry said half-door into and out of alinement with the body door. 100

12. In an inclosure for the compartment of an automobile having a hinged door, a door structure that includes an attachment member longitudinally movable over the side of the compartment, a frame hinged to the attachment member and movable through a horizontal plane about its hinges, a half-door hinged to said frame and complementary to the body door; the attachment member being movable to carry said half-door into and out of alinement with the body door; and means for detachably clamping the two doors 110 against relative movement when they are in alinement. 120

13. In an inclosure for the compartment of an automobile having a hinged door, a door structure that includes an attachment member longitudinally movable over the side of the compartment, a frame hinged to the attachment member and movable through a horizontal plane about its hinges, a half-door hinged to said frame and complementary to 130

the body door; the attachment member being movable to carry said half-door into and out of alinement with the body door; said frame and half-door being so relatively mounted that they are capable of simultaneous pivotal movement in opposite directions about their hinges; and means for detachably

clamping the two doors against relative movement when they are in alinement.

In witness that I claim the foregoing I 10 have hereunto subscribed my name this 10th day of May, 1924.

CHARLES E. RUTTAN.
